UNITED STATES PATENT OFFICE

153,348

DESIGN FOR A COMBINED MOTOR VEHICLE
SERVICE CABINET AND TABLE

Margaret Gainsbro, Dallas, Tex.

Application July 3, 1946, Serial No. 131,221

Term of patent 14 years

(Cl. D33—19)

To all whom it may concern:

Be it known that I, Margaret Gainsbro, a citizen of the United States of America, residing at Dallas, county of Dallas, State of Texas, have invented a new, original, and ornamental Design for a Combined Motor Vehicle Service Cabinet and Table, of which the following is a specification, reference being had to the accompanying drawing, forming a part thereof, wherein;

Fig. 1 is a perspective view of a combined motor vehicle service cabinet and table, with the table in closed position, showing my new design.

Fig. 2 is a similar view, showing the table in open position.

Fig. 3 is a front view.

Fig. 4 is a rear view.

Fig. 5 is a side view.

I claim:
The ornamental design for a combined motor vehicle service cabinet and table, as shown.
MARGARET GAINSBRO.
